(**) Term: **14 Years**

(57) **CLAIM**

The ornamental design for a casing of a water purifier apparatus, as shown and described.

DESCRIPTION

Mar. 2, 2001 (CH) 127880

(51) LOC (7) Cl. **23-01**

FIG. 1 is a perspective front view of the casing;

(52) U.S. Cl. **D23/207**

FIG. 2 is a perspective view thereof from the left front;

(58) Field of Search **D23/207, 209;**

FIG. 3 is a perspective view thereof from the right front;

210/232, 435, 140, 190

FIG. 4 is a rear perspective view thereof; and,

(56) **References Cited**

FIG. 5 is a top plan view thereof.
